UNITED STATES PATENT OFFICE.

BOUGHTON U. EDDY, OF PITTSFIELD, MASSACHUSETTS, ASSIGNOR TO GENERAL ELECTRIC COMPANY, A CORPORATION OF NEW YORK.

TUBE-LOADING MACHINE.

1,331,902.

Specification of Letters Patent. Patented Feb. 24, 1920.

Application filed May 26, 1916. Serial No. 100,120.

To all whom it may concern:

Be it known that I, BOUGHTON U. EDDY, a citizen of the United States, residing at Pittsfield, county of Berkshire, State of Massachusetts, have invented certain new and useful Improvements in Tube-Loading Machines, of which the following is a specification.

My invention relates to a machine for loading material and particularly powdered material into a tube, and has for its object the provision of a machine of this character which is simple and rugged in construction, and which carries out the operation expeditiously.

In the manufacture of sheathed wire, of the character disclosed in Patent #1,107,233, which was issued to Chester N. Moore, August 11, 1914, a preparatory ingot is formed by placing centrally in a tube of suitable material such as steel or copper, a core wire, and powdered insulating material, such as magnesia, is then compacted between the two. It is necessary that the material should be densely and uniformly compacted between the core wire and the sheath, otherwise in the succeeding operations the core wire will not be drawn down to a uniform diameter, and the sheathed wire will be unsatisfactory. The machine made in accordance with my present invention is well adapted to expeditiously load the tubes in the desired manner. While I have illustrated a machine that is particularly adapted for this particular application, it will be understood that it is not limited to such application, but is well adapted for general use.

For a fuller understanding of my invention, reference may be had to the accompanying drawings in which Figure 1 is a side elevation of a machine embodying my invention; Fig. 2 is a front elevation thereof; Fig. 3 is a cross section taken on the line *a—a*, Fig. 2, and looking in the direction of the arrows; Fig. 4 is a detail view showing the attachment between the plunger and the head to which it is secured; Fig. 5 is a bottom plan view of the part shown in Fig. 4; Fig. 6 is a vertical section through the hopper for the powdered material; and Fig. 7 is a longitudinal section of a tube to be filled and

the plunger which compacts the material therein.

Referring now to the drawings, A is the frame for the machine, which comprises a base plate 1, from which ascends the supporting frame 2, which is U-shaped in cross section as shown in Fig. 3. The front of the vertical frame is formed with a channel 2^a (see Fig. 3), which constitutes a guide for a yielding supporting base 4 for the tube to be filled. In the form here shown this supporting base is connected to a counterweight 5, by means of a wire rope or other flexible connection 6, which passes over a sector 7, loosely mounted on a shaft 8 passing through the machine. The tube 9, which is to be loaded with material, and centrally of which is the core wire 10, is seated at its lower end in a head 11, and at its upper end in the bottom of a funnel 13, so that the tube registers with the opening through the funnel. The head 11 is carried by a bracket 12 attached to the base 4. The head 11 is directly mounted on a screw shaft 15 which passes through an internally threaded revoluble sleeve 14 mounted on the bracket 12. This sleeve is provided with a bevel gear 16 with which meshes a gear 17 secured on a shaft which is journaled in the upper end of bracket 12, which shaft is provided with a handle 18 by means of which gears 16 and 17 are rotated, and the head 11 raised and lowered with respect to the supporting base 4. The material is compacted in the tube by a plunger 19, which is provided with a central opening 19^a (see Fig. 7) in which the core wire is received. The plunger is reciprocated by a head 20 which is guided in the same channel 2^a as the supporting base 4. The plunger is provided at its upper end with an enlarged head 21 (see Fig. 4) which is beveled at its upper edge and which is engaged by a pivoted arm 22 which is forced beneath the head by a spring 23, so that the head of the plunger is held in position against the head 20.

The head 20 is reciprocated and the machine may be operated by an electric motor 100 24, to the shaft of which is secured a pinion 25. This pinion engages a gear 26 mounted on a counter shaft, to the other end of which is secured a gear 27. This gear in turn en-

gages a gear 28, secured to a shaft 37. A gear 29 is loosely mounted on the shaft 37 and meshes with a gear 30, secured to a shaft on the outer end of which is secured a disk 31, provided with a counterweight 32. The disk 31 is connected to the supporting head 20 by a link 33, the upper end of which is adjustably secured to the disk 31 by means of a clamping member 34, provided with a series of teeth engaging corresponding teeth 35 on the disk 31. The lower end of the link 33 is pivoted at 33^a to the supporting head 20. The motor is connected to, and disconnected from the disk 31 by means of a clutch 36 surrounding the shaft 37 and operated by an arm 38. The arm 38 which actuates the clutch is pivoted at 39.

In accordance with my invention, the material to be compacted within the tube is gradually fed thereto. Preferably the feeding operation is carried out by a mechanism which feeds successively the charges of the material to the tube and this mechanism includes a hopper B which comprises a container or receptacle 40. This receptacle is mounted on a bracket 41 secured to the frame of the machine. A shaft 42 extends centrally through the hopper above and below the same. A disk or plate 43 is disposed in the bottom of the container 40 and is provided with a plurality of openings 44, each of which is designed to contain the proper amount of powdered material to be introduced into the tube in a single charge. The plate 43 is provided with a shank 45 which may be integral with the plate and which extends upwardly through the hopper and which is secured together with the plate to the shaft 42. Located immediately above the disk or plate 43 is a stationary cover plate 46, which is provided with a shank 47 surrounding the shank 45 of the plate 43. The plate 46 is provided with an opening 48 so that when one of the openings 44 of the plate 43 is brought beneath the plate 43, the opening of the plate 43 will be filled with the powdered material which is to be introduced into the tube. A tube 49 communicates with the bottom of the hopper and with the funnel 13, and when one of the openings 44 charged with powder is brought over the tube in the manner which will be hereinafter more fully described, the charge of powder is fed to the funnel. In order to intermittently move the shaft 42 and the disk or plate 43 which is secured thereto angularly, the upper end of the shaft is provided with a clutch C which is operated by a pin 50 carried by a bracket 50^a on the head 20. One member 51 of the clutch is secured to the upper end of the shaft 42. This member, which is in the form of a cylinder, is formed on its lower side with ratchet teeth C, as shown in Fig. 2. The coöperating member 52 of the clutch is also substantially cylind-

rical in form and is provided at its upper end with ratchet teeth engaging those of the member 51. The member 52 is held in engagement with the other member of the clutch by means of a spring 53, interposed between the lower end of the clutch member 52 and a boss 54 formed on the frame. The member 52 is provided with a spiral groove 55 which is engaged by the pin 50, carried by the bracket 50^a. During the upward movement of the head 20, pin 50 engages the spiral groove and rotates member 52, and as the teeth formed thereon engage the teeth of the other member of the clutch, the shaft 42 is rotated, and with it the disk or plate 43, to cause a charge of powder in one of the openings in the plate to be brought over the upper end of the tube 49. When the head 20 moves downwardly, the clutch member 52 is rotated in the opposite direction; during this movement, the teeth formed on the other member 51 of the clutch, and the shaft 42 and the parts coöperating therewith, remain in the same position in which they were left at the end of the upward movement of the head 20. It will, of course, be understood that the openings 44 formed in the disk 43 are so designed with reference to the angular movement of the clutch member 52, that one of the openings will be brought in position to empty a charge of material into the tube 49 each time the head 20 is reciprocated.

Since the plunger 19 surrounds the core wire 10 of the tube, and is withdrawn from the tube after each compacting operation, and since the supporting base for the tube is advanced at each compacting operation, it is necessary to release the plunger at the same distance or substantially the same distance from the tube after each compacting operation and in a position where it surrounds the core wire; otherwise, if the plunger were withdrawn from the core wire and the latter failed to register exactly with the opening in the plunger, the core wire would be crumpled when the plunger next entered the tube. In order to prevent the plunger from being withdrawn from the projecting end of the core wire, the plunger is released at each upward movement of the head 20 by a cam member 56 carried by a bar 57, which is secured at its lower end to the supporting base 4. Since the cam 56 remains at the same distance from the supporting base, it is apparent that the plunger will always be released at the same distance without the tube 9, and may readily be so designed that it will be left in a position surrounding the core wire. I have here shown the lower end of the bar 57 provided with a rack 58 which is engaged by a pinion 58^a. This is for the purpose of adjusting the head of the bar and accordingly adjusting the position at which the plunger will be released. The pinion 58^a is locked in

any desired position by a lock nut (not shown in the drawing). The position of release of the plunger may thus be varied in accordance with the length of the tube to be 5 filled.

The movable supporting base 4 for the tube and the counterweight are locked in successively advanced positions by the following mechanism: A pawl 59 carried on a 10 stud 60 secured to one side of the segment 7 (see Fig. 3) engages a ratchet wheel 61, carried on one end of a shaft 62, journaled in a bearing in the segment 7. On the other end of the shaft 62 is a pinion 63, which engages a spur gear 64 which is keyed on the 15 shaft 8. A worm gear 65 is secured to the outer end of the shaft 8, and is engaged by a worm wheel 66, mounted on a shaft 67 and controlled by a hand wheel 68. It will be 20 seen that as the tube is filled with successive charges of powder, the supporting base 4 is moved downwardly against the counterweight 5, and during this movement the pinion 63 rides over the spur gear 64 and 25 the teeth of the ratchet wheel 61 ride beneath the pawl 59. The engagement of the pawl with the ratchet wheel, however, prevents the counterweight from returning to its original position. It will be understood that 30 during the loading operation, the shaft 8 is not moved but is secured in position by the worm wheel 65 and the coöperating worm gear 66.

In order to break the driving connection 35 between the motor and the disk 31 which operates the plunger at the time the tube is filled, a lever 69 is provided which is pivoted at 70 and the lower end of which is in the path of movement of a pin 71, carried by a 40 strap or member 72 which is secured to the segment 7 by an intermediate sleeve and is movable therewith. The member 69 is connected by a link 73 to the handle 38. Now when the tube 9 has been filled, the base 4 45 has been moved downwardly, and the segment 7 has passed through a sufficient angular movement to cause the pin 71 to engage the lower end of the lever 69 to operate the clutch.

The operation of the machine embodying 50 my invention will be readily understood from the above description, and is as follows: A tube with a core wire is secured in position in the manner described above; the 55 machine is then started in operation and at each revolution of the disk 31 a charge of powdered material is introduced into the funnel and to the tube in the manner described above, and is compacted in the tube 60 by the movement of the plunger. Successive charges are similarly introduced to the tube and compacted therein, the supporting base for the tube being advanced and locked in successively advanced positions as 65 described above. When the tube has been com-

pletely filled, the clutch breaks the driving connection between the motor and the plunger, and the machine may then be stopped until the filled tube is removed and an empty one inserted in its place. The 70 weight is then returned to its lowered position by turning the hand wheel 68.

While I have described my invention as embodying a concrete structure and as operating in a specific manner, in accordance 75 with the requirements of the patent statutes, it should be understood that my invention is not limited thereto, since various modifications thereof will suggest themselves to those skilled in the art without departing 80 from the spirit of my invention, the scope of which is set forth in the annexed claims.

What I claim as new and desire to secure by Letters Patent of the United States, is,—

1. A machine for loading material into a 85 tube, comprising a yielding base for supporting the tube, means for gradually introducing the material into the tube, means for compacting the same therein and simultaneously advancing the base, and means for 90 maintaining said base in its gradually advanced positions.

2. A machine for loading material into a 95 tube, comprising a yielding base for supporting the tube, means for introducing successive charges of material to said tube, means for successively compacting the same therein, and means for maintaining said base in its successively advanced positions 100 during the loading operation.

3. A machine for loading material into a 105 tube, comprising a base for supporting the tube, a counterweight for said base, means for introducing successive charges of material to said tube, means for successively compacting the same therein, and means for maintaining said base in its successively advanced positions during the loading operation.

4. A machine for loading material into a 110 tube which has a core wire projecting therefrom, comprising a yielding base for supporting the tube, means for introducing successive charges of material into said tube, a reciprocating head, a plunger releasably 115 secured thereto, and means for releasing said plunger without said tube and in a position surrounding the core extension after each packing operation.

5. A machine for loading material into a 120 tube, comprising a yielding base for supporting the tube, a reciprocating head, means coöperating with said head for introducing successive charges of material into said tube, a plunger secured to said head 125 for compacting successive charges of material in the tube, and means for maintaining said base in its successively advanced positions during the loading operation.

6. A machine for loading material into a 130

- 10 tube which has a core wire projecting therefrom, comprising a yielding base for supporting the tube, means for introducing successive charges of material into said tube, a plunger surrounding the core wire for packing the successive charges of material in said tube, a reciprocating member to which the plunger is attached, means for maintaining said base in its successively advanced positions during the packing operation, and means for releasing said plunger without said tube and in a position surrounding the extension after each packing operation.
- 15 7. A machine for loading material into a tube which has a core wire projecting there-

from, comprising a yielding base for supporting the tube, means for introducing successive charges of material into said tube, a reciprocating head, a plunger releasably secured thereto for compacting the successive charges of material in the tube, means for releasing said plunger without said tube and in a position surrounding the core extension after each packing operation, and means for adjusting the position of release of the head.

In witness whereof I have hereunto set my hand this twenty-third day of May, 1916.

BOUGHTON U. EDDY.
